UNITED STATES PATENT OFFICE.

ELMER V. SANTEE, OF WILLIAMSON, NEW YORK.

STONE GATHERER.

Application filed July 8, 1926. Serial No. 121,163.

This invention relates to stone gatherers, and has for one of its objects the provision of a novel, comparatively simple and highly efficient machine adapted for the purpose of gathering and loading stones onto a wagon.

With the foregoing and other objects in view, the nature of which will become apparent as the description proceeds, the invention consists of the construction, combination and arrangements of parts herein-after fully described and claimed, and illustrated in the accompanying drawings, wherein:

Figure 1 is a view in side elevation of the machine,

Figure 2 is a sectional view taken on the planes indicated by the line 2—2 of Figure 1,

Figure 3 is a sectional view taken on the planes indicated by the line 3—3 of Figure 1, and

Figure 4 is a view partly in section and partly in plan of the rear portion of the machine.

Corresponding and like parts are referred to in the following description, and designated in the several views of the accompanying drawings, by similar reference characters.

The machine comprises ground wheels 1, an axle 2 and a bolster 3. Gears 4 are secured to the inner sides of the wheels 1, and a draft yoke 5 is connected to the axle 2 by cuffs 6. The draft yoke 5 is pivotally connected as at 7 to the cuffs 6, and the latter are loose on the axle 2.

A hollow cylindrical body or casing 8 is secured to the bolster 3 and occupies a downwardly and forwardly inclined position. A spiral conveyor 9 is rotatably mounted with in the casing 8, and the rearward or upper end of the shaft 10 thereof has secured thereto a pinion 11. This end of the casing 8 is closed and provided with a bearing 12 for the shaft 10. The forward or lower end of the casing 8 is fully open and rake teeth 13 are located at its lower side. The teeth 13 extend downwardly and forwardly with respect to the casing 8 and are adapted to penetrate the ground while the machine is in use. The casing 8 is provided at its rearward end with a discharge opening 14 below which is located a chute 15. In its upper side the casing 8 is provided with openings 16 to permit of access being gained to the spiral conveyor 9. These openings are closed by covers 17 which are hinged as at 18 to the casing 8

and are adapted to be secured in closed position by any suitable means such as that shown at 19.

The spiral conveyor 9 is adapted to be driven from the wheels 1 through the medium of shafts 20 and 21 which are connected to the gears 4 and pinion 11. The shafts 20 and 21 are journaled in bearings 22 carried by the bolster 3 and in bearings 23 carried by the casing 8, and each of the shafts consists of two sections connected by a universal joint 24. Gears 25 which are loose on the shafts 20 and 21 and mesh with the pinion 11, establish a driving connection between the shafts and the spiral conveyor 9. The gears 25 are provided with annular series of ratchet teeth 26 with which similar series of ratchet teeth 27 on sleeves 28 engage. The sleeves 28 are slidably mounted on the shafts 20 and 21, and the ratchet teeth thereof are yieldingly held in engagement with the ratchet teeth of the gears 25 by springs 29 which are mounted upon the shafts between the sleeves and bearings 23. Pins 30 which are carried by the shafts 20 and 21 and pass through slots 31 in the sleeves 28, establish a driving connection between the shafts and sleeves. A gear 32 which is fixed to the shaft 20 and meshes with the adjacent gear 4, establishes a driving connection between this shaft and the adjacent wheel 1. A driving connection between the shaft 21 and the other wheel 1 is established by means of a gear 33 fixed to this shaft, a gear 34 journaled on the bolster 3 and meshing with the gear 33, and a gear 35 fixed to the gear 34 and meshing with the gear 4 of this wheel 1. The shafts 20 and 21 are rotated in a common direction and exert a uniform driving pressure on the spiral conveyor 9. The rear ends of the shafts 10, 20 and 21 are connected by a bar 36 provided with bearings 37 for the reception of the ends of the shafts and connected to the shaft 10 by an element 38. The ratchet connection between the shafts 20 and 21 and the gears 25 permit the machine to be backed or turned to the right or left without danger of slipping or otherwise injuring gears of the driving connection between the wheels 1 and the spiral conveyor 9.

A rake 39 is connected to the lower end of the casing 8 by means of a sleeve 40 which is bolted or otherwise detachably secured in place. The sleeve 40 is provided with a forward tapered extension 41 which

is open at its front and bottom sides and carries the rake teeth 13. The rake 39 comprises forwardly diverging bars 42 which are connected to the sleeve extension 41 for movement about vertical axes 43 and horizontal axes 44. The rake bars 42 are of sectional formation, and the adjacent ends of the sections thereof are connected for movement about vertical axes 45 and horizontal axes 46. As the sections of the rake bars 42 are connected together and to the sleeve extension 41 for movement about horizontal axes, they will readily accommodate themselves to any unevenness of the ground and as the result hold their teeth 47 in contact with the ground at all times. The teeth 47 extend downwardly, inwardly and forwardly from the lower edges of the bars 42, and are, together with the teeth 13, prevented from penetrating the ground beyond a certain depth by shoes 48 secured as at 49 to the sleeve extension 41 and shoes 50 secured as at 51 to the rake bars. The rake bars 42 are held against movement on their pivots 43 and 45 by a cross bar 52 which rests upon the rake bars and is secured thereto by pins 53, the pins being carried by the rake bars and passing through certain openings of the forwardly diverging rows of openings 54 in the cross bar. The cross bar 52 is provided in its ends with extensions 55 which overlie the front sections of the rake bars 42 and are connected to the cross bar by hinges 56. The front ends of the cross bar extensions 55 are laterally enlarged as shown at 57 and are provided with slots 58. A pin 59 carried by each of the front sections of the rake bars 42, and passing freely through the slots 58 in the cross bar extensions 55, permit the front rake bar sections to be adjusted relatively about their vertical pivots 45 and secured in adjusted position. The slots 58 extend in the direction of the length of the rake bars 42 so as to permit the rake bar sections to move about their horizontal axes 44 and 46.

In practice, the machine may be connected to a tractor or team through the medium of the draft yoke 5 which extends forwardly from the axle 3 and about the casing 8. As the machine is drawn over the ground, the spiral conveyor 9 will be rotated with the result that the material entering its front end will be carried through the casing 8 to the discharge opening 14. The material passing through the discharge opening 14 will be directed by the chute 15 into a wagon traveling alongside the machine. The material directed into the front end of the casing 8 will be gathered from over a wide area due to the angular arrangement of the rake bars 42. The forward end of the spiral conveyor 9 is tapered and extends into the extension 41 of the sleeve 40.

It should be understood that the draw-

ings are merely illustrative and do not pretend to give exact proportions. Furthermore, the said drawings are illustrative of a preferred construction, it being my expectation that various changes and modifications 70 may be made without departing from the spirit and scope of my invention.

What is claimed is:—

1. A machine of the character set forth, comprising a downwardly and forwardly 75 inclined casing provided at its rear end with a discharge opening, wheels supporting the casing, a spiral conveyor within the casing, means connected to the front end of the casing for directing material into the same, a pinion fixed to the conveyor, shafts, gears loose on the shafts located at opposite sides of the conveyor and meshing with the pinion, ratchet mechanism establishing driving connection between the shafts and gears, 80 and means establishing driving connection between the shafts and wheels.

2. A machine of the character set forth, comprising a downwardly and forwardly inclined conveyor, means for operating the conveyor, forwardly divergent sectional bars provided with rake teeth and located at the front end of the conveyor, and means 90 for pivotally connecting the bar sections.

3. A machine of the character set forth, comprising a downwardly and forwardly inclined conveyor, means for operating the conveyor, forwardly divergent sectional bars provided with rake teeth and located 95 at the front end of the conveyor, and means for pivoting the bar sections for movement about vertical and horizontal axes.

4. A machine of the character set forth, comprising a downwardly and forwardly inclined conveyor, means for operating the conveyor, forwardly divergent sectional bars provided with rake teeth and located 105 at the front end of the conveyor, means for pivoting the bar sections for movement about vertical and horizontal axes, and means releasably holding the bar sections against movement about their vertical axes.

5. A machine of the character set forth, including a downwardly and forwardly inclined casing provided at its rear end with a discharge opening and provided at its front end with a forwardly directed tapered extension open at its front and bottom sides, a spiral conveyor within the casing and having its forward end tapered and extending into said extension, and conveyor operating means.

6. A machine of the character set forth, including a downwardly and forwardly inclined conveyor, forwardly divergent bars provided with rake teeth and located at the front end of the conveyor, means mounting the bars to permit them to be adjusted laterally with respect to each other, and means holding the bars in adjusted relation.

7. A machine of the character set forth, including a downwardly and forwardly inclined conveyor, forwardly divergent bars provided with rake teeth and located at the front end of the conveyor and capable of relative lateral adjustment, and means holding the bars in adjusted relation.

8. A machine of the character set forth, including a downwardly and forwardly inclined conveyor, forwardly divergent bars provided with rake teeth and located at the front end of the conveyor and capable of relative lateral adjustment, means holding the bars in adjusted relation, said means embodying a cross bar provided with forwardly divergent rows of openings and an element carried by each of said first bars and passing through an opening of each of the rows of openings.

9. A machine of the character set forth, including a downwardly and forwardly inclined conveyor, forwardly divergent bars provided with rake teeth and located at the front end of the conveyor, means mounting the bars for relative adjustment about vertical axes and for movement about horizontal axes, and means holding the bars in adjusted relation.

10. A machine of the character set forth, including a downwardly and forwardly inclined conveyor, forwardly divergent bars provided with rake teeth and located at the front end of the conveyor, means mounting the bars for relative adjustment about vertical axes and for movement about horizontal axes, each bar consisting of sections, means connecting the bar sections for relative adjustment about vertical axes and for movement about horizontal axes, and means holding the bars and bar sections in adjusted relation.

11. A machine of the character set forth, including a downwardly and forwardly in-

clined conveyor, forwardly divergent bars provided with rake teeth and located at the front end of the conveyor, means mounting the bars for relative adjustment about vertical axes and for movement about horizontal axes, means holding the bars in adjusted relation, the bars being sectional, and means connecting the sections of each bar for relative adjustment about vertical axes and for movement about horizontal axes, said second means holding the bar sections in adjusted relation while permitting the bar sections to move about their horizontal axes.

12. A machine of the character set forth, including a downwardly and forwardly inclined conveyor, forwardly divergent bars provided with rake teeth and located at the front end of the conveyor, means mounting the bars for adjustment about vertical and horizontal axes, the bars being of sectional formation, means connecting the bars sections for adjustment about horizontal and vertical axes, a cross bar provided with forwardly divergent rows of openings, elements carried by certain of the bar sections and passing through certain of said openings, extensions hinged to the cross bar and having laterally enlarged free ends provided with openings, and elements carried by the other bar sections and passing through certain of the openings in said extensions.

13. A machine of the character set forth, including a downwardly and forwardly inclined conveyor, forwardly divergent bars provided with rake teeth and located at the front end of the conveyor, means mounting the rear ends of the bars for movement about horizontal axes, and shoes connected to and supporting the front ends of the bars.

In testimony whereof I affix my signature.

ELMER V. SANTEE.
